CLAIM

The ornamental design for a low profile staple, as shown and described.

DESCRIPTION

FIG. 1 is a perspective view of a low profile staple, according to the first embodiment of the present disclosure; FIG. 2 is a front side view of a low profile staple, according to the first embodiment of the present disclosure; FIG. 3 is a rear side view of a low profile staple, according to the first embodiment of the present disclosure; FIG. 4 is a rear side view of a low profile staple, according to the first embodiment of the present disclosure; FIG. 5 is a left side view of a low profile staple, according to the first embodiment of the present disclosure; FIG. 6 is a top view of a low profile staple, according to the first embodiment of the present disclosure; FIG. 7 is a bottom view of a low profile staple, according to the first embodiment of the present disclosure; FIG. 8 is a perspective view of a low profile staple, according to the second embodiment of the present disclosure; FIG. 9 is a front side view of a low profile staple, according to the second embodiment of the present disclosure; FIG. 10 is a rear side view of a low profile staple, according to the second embodiment of the present disclosure; FIG. 11 is a right side view of a low profile staple, according to the second embodiment of the present disclosure; FIG. 12 is a left side view of a low profile staple, according to the second embodiment of the present disclosure; FIG. 13 is a top view of a low profile staple, according to the second embodiment of the present disclosure; and, FIG. 14 is a bottom view of a low profile staple, according to the second embodiment of the present disclosure.

The broken lines in the drawings illustrate portions of the low profile staple and form no part of the claimed design.
